PACKING COMPANY, OF CANAJOHARIE, NEW YORK, A CORPORATION OF NEW YORK.

HERMETIC CLOSURE FOR RECEPTACLES.

1,150,780.

Specification of Letters Patent. Patented Aug. 17, 1915.

Application filed December 23, 1910. Serial No. 599,057.

To all whom it may concern:

Be it known that I, WILLIAM A. LORENZ, a citizen of the United States, residing at Hartford, in the county of Hartford and 5 State of Connecticut, have invented new and useful Improvements in Hermetic Closures for Receptacles, of which the following is a specification.

This invention relates to closure joints for 10 vacuum sealed jars or other packages in which the seal is maintained by an elastic gasket compressed in the joint between the receptacle and its cap or cover by atmospheric pressure, due to the vacuum induced 15 within the package.

The invention is particularly adapted to the sealing of packages, the component parts of which are suitable for household or other uses, after the package is opened and its 20 original contents have been disposed of. Largely because of the inherent difficulties in the secure and reliable commercial sealing of these packages, the component parts thereof are usually adapted in form and material to their initial purpose of forming 25 a reliable sealed package, and without any provision for subsequent uses, the meeting rims being either grooved or shouldered, or thin and flexible, or in some other way 30 disqualified for subsequent permanent service, excepting as a cover, or for some other inferior and temporary use.

In a number of prior patents I have shown, 35 described and claimed various forms of closures which may be successfully applied to the sealing of plain rimmed receptacles, such as tumblers; but in most of these cases, the cover employed is merely a cap made of tin or other thin and flexible metal, having 40 a downwardly turned thin edged flange which overlaps and projects below the lower edge of the receptacle, and forms a lapped or telescoping joint with the receptacles, either on the inner or outer side thereof, the 45 flexibility of the thin flange enabling it to conform to the variations and inequalities incident to the manufacture of the tumblers.

It is an important object of the present invention to provide for sealing together

two plain rimmed receptacles, either or both 50 of which may be of metal, or of glass or similar material having rounded and substantially inflexible edges, and otherwise suitable for household use, as cups, dishes, saucers, or pans, etc. According to the present invention the plain rims of these receptacles are of approximately equal perimeter, or so nearly equal that they will not interlap or telescope together. These rounded rims are disposed in abutting proximity to 60 each other, with a sealing gasket between them, and are therefore joined by what may be termed an abutting or "butt" joint, as distinguished from the interlapping or "lap" joints which are commonly used in 65 the hermetic sealing of cans and jars.

Figure 1 of the drawings is an elevation in cross-section showing a package of which the body portion is in the general form of a tumbler, while the cover portion is in the 70 general form of a saucer. In this figure, the parts are shown in their unsealed air-exhausting position. Fig. 2 is an elevation of the package shown in Fig. 1, showing it in its sealed condition, a portion being 75 broken away to show the sealed joint in cross-section. In these two figures the abutting rims of the two receptacles are of slightly different diameter. Fig. 3 is an elevation in cross-section of a package composed of two similar receptacles, which in this case are shown to be made of sheet metal, with its edges turned over. In this view the package is shown in its unsealed or 80 exhausting position. Fig. 4 is a side elevation, showing the package of Fig. 3 in its sealed condition, a portion being broken away to show the gasket joint.

The receptacle 11 (Figs. 1 and 2) has a plain rim 15 upon which rests the gasket 13, 90 which supports the cap or cover 12, which also has a plain rim 16. Both the receptacle 11 and the cap 12 are of common household form, the cap being made in the form of a shallow dish or saucer while the receptacle 95 or body is in the form of a deeper tumbler or bowl. The parts are guided in proper sealing relation to each other by a band 14,

which encircles the package joint and the outer surface of the gasket 13. This band sustains the gasket so that the latter cannot escape being compressed when the cap 12 is forced downward. Hence the rubber is crowded against the band and into the space between the band and the cap and receptacle, and covers a large area of each rim. One or more apertures 17 are provided in 10 the band through which a knife or other suitable implement may be thrust to puncture the gasket and admit air when it is desired to open the package.

The rim 16 of the cap 12 is here shown as 15 being made a little larger in diameter than the rim 15 of the receptacle body 11, which is here shown as an ordinary glass tumbler. Owing to this difference in diameter the pressure on the cap has a wedging action, 20 which gives an effective pressure upon the gasket 23 greater than would be exerted by a direct downward pressure, such as shown in the other figures. This is by no means an essential feature; but for packages of 25 small diameter having a comparatively small area upon which the atmospheric pressure may act, the wedging action may be found preferable, since it increases the effective sealing pressure upon the gasket. In 30 this construction, the band 14 not only retains the gasket in proper relation to the joint, but also forms a circumferential reinforcement for the edges of the body and cover, to protect them from being split or 35 chipped.

In the package shown in Figs. 3 and 4, the body portion 21 and cover portion 22 are shown to be of the same size and form. They are herein represented as being made 40 of sheet metal, having their edges rolled, or seamed, or folded, to avoid presenting sharp edges, thus forming rounded rims 25 and 26 between which is seated the gasket 23, which in this instance is shown to be circular in 45 cross-section. In this instance the circular band 24 is shown to be shaped concave on its inner surface, to facilitate seating and maintaining the band and the gasket in proper relation to each other. The lower 50 and upper edges 29 are preferably made to overlap the rims 25 and 26, respectively, of the package, thus maintaining the latter in proper sealing relation to each other and to the gasket, both before and during the sealing operation. In this case, as in Figs. 1 and 2, the band may be regarded as a carrier for the respective gaskets, the rims of the respective packages sliding or telescoping 55 into the band, against the opposite sides 60 of the gasket. Obviously, any of these bands may be placed upon the inner side of the joint, receiving the gaskets and the receptacle rims against their outer sides. But for general purposes, and especially where

the receptacles are made of glass or other 65 brittle material, I consider it preferable to employ the band upon the exterior surface of the joint, as herein shown, since in that case they not only serve to guide and support the parts during the sealing operation, 70 but also serve the additional purpose of protecting the edges of the receptacles from being broken or chipped during subsequent handling or transportation.

The rounded rims confine and concentrate 75 their pressure upon a relatively narrow zone of the gasket forming a continuous line of pressure around it, forcing the surplus rubber away from that line, and thus establishing an effective endless circle of sealing contact, the pressure upon which is by reason of 80 convex rims much greater than it would be if distributed over the greater area of the flat rims or the flat gaskets now more commonly used. Moreover, it is exceedingly 85 difficult to manufacture vessels or receptacles having a comparatively rigid and inflexible rim, with sufficient accuracy, so that the rims will meet in a flat plane. On account of the rims being thus more or less 90 wavy, they will, when opposed, or abutted together, generally touch each other only at intervals around the joint. Such inequalities must be compensated for by the gasket 95 inserted between them; and in the present 100 invention this is done more reliably and completely by the use of the rounded rims than by the use of flat rims, since the narrow lines of pressure seat more deeply into the gasket, thereby stretching and fulling 105 the gasket at the side or sides of the line of pressure.

I claim as my invention:—

1. The combination of a receptacle and cover having convexly rounded rims disposed in abutting proximity to each other, a gasket interposed between and receiving the opposing rounded rims along the middle zones of the upper and lower surfaces of the gasket, and a metallic band on the outer circumference of the gasket, provided with an opening to facilitate opening the joint.

2. The combination of a receptacle and cover having rounded rims disposed in abutting proximity to each other, a gasket interposed between the opposing rounded rims and provided with circumferential grooves in its upper and lower surfaces for seating and locating the said opposing rims in concentric sealing relation to each other, and a metallic band extending circumferentially around the outer surface of the gasket, and provided with an aperture to facilitate opening the joint.

3. The combination of a receptacle and cover having rounded rims disposed in abutting proximity to each other, a gasket interposed between and receiving the opposing

rounded rims against the middle zone of the upper and lower surfaces of the gasket and a band interlapping the said rims and the gasket to support and reinforce the sealed joint, the band being provided with an opening to facilitate the opening of the joint.

In testimony whereof I have signed my name to this specification in the presence of two subscribing witnesses.

WILLIAM A. LORENZ.
